Primary Examiner — George D. Kirschbaum*Assistant Examiner* — Maria J Edwards(74) *Attorney, Agent, or Firm* — Michele J. Young(57) **CLAIM**

We claim the ornamental design for a protective glove, as shown and described.

DESCRIPTION

FIG. 1 is a perspective view of a protective glove showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in FIGS. 1-7 represent stitching and form no part of the claimed design.

1 Claim, 5 Drawing Sheets(56)
